UNITED STATES PATENT OFFICE

96,750

DESIGN FOR A RADIOCABINET

Alfred G. Hoffman, Cincinnati, Ohio, assignor to
Midwest Radio Corporation, Cincinnati, Ohio

Application May 17, 1935, Serial No. 56,884

Term of patent 7 years

To all whom it may concern:

Be it known that I, Alfred G. Hoffman, a citizen of the United States, residing at 909 Broadway, in the city of Cincinnati, county of Hamilton, and State of Ohio, have invented a new, original, and ornamental Design for a Radiocabinet, of which the following is a specification, reference being had to the accompanying drawing, forming part thereof.

The figure is a front perspective view of a radiocabinet, showing my new design.

I claim:

The ornamental design for a radiocabinet, as shown.

ALFRED G. HOFFMAN.
